Primary Examiner — Sheryl Lane*Assistant Examiner* — Jennifer M Campbell(74) *Attorney, Agent, or Firm* — Stephen J. Weyer, Esq.;
Stites & Harbison, PLLC(57) **CLAIM**

The ornamental design for a brassiere, as shown and described.

DESCRIPTION

FIG. 1 is a front, right side, and top perspective view of the brassiere, shown lying flat, in accordance with the present design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right elevational view thereof, the left side being a mirror image thereof; and,

FIG. 7 is a front, right side, and top perspective view of the brassiere, shown when worn in accordance with the present design.
